United States Patent Office.

GILBERT F. TAYLOR, OF NEW YORK, N. Y.

Letters Patent No. 82,566, dated September 29, 1868.

IMPROVED GUARD FOR CARPET-SWEEPING MACHINES.

The Schedule referred to in these Letters Patent and making part of the same.

TO ALL WHOM IT MAY CONCERN:

Be it known that I, GILBERT F. TAYLOR, of New York, in the county of New York, and State of New York, have invented a new and useful Improvement in Guards for Carpet-Sweeping Machines; and I do hereby declare that the following is a full, clear, and exact description thereof, which will enable others skilled in the art to make and use the same, reference being had to the accompanying drawings, forming part of this specification, in which—

Figure 1 is a plan or top view of my invention.

Figure 2 is a transverse section of the same, taken in the line $x-x$, of fig. 1.

Similar letters of reference indicate like parts.

The carpet-sweeping devices, which are now much used instead of the ordinary brooms, on account of not raising any dust during the sweeping-operation, have only one material objection, and that is, that furniture is very liable to be disfigured and injured by the case of the implement being brought in contact with the legs of chairs and tables, &c., the hard metallic cases, even by a very slight contact or rub, abrading the varnish, and leaving unsightly scratches.

My invention consists in the application of a pad to the case, the pad being constructed and arranged in such a manner that it will effectually prevent the abrasion of furniture, and admit of being readily applied to and detached from the case.

In the accompanying sheet of drawings, A represents the case of a carpet-sweeping machine, B the cylindrical brush, and d the dust-chambers.

These parts may be constructed in the usual way, and therefore do not require a special description.

C is a pad or cushion, made in the form of a narrow bag, and out of leather, prepared cloth, or other suitable material, stuffed with hair, moss, or other substance.

The ends of this pad or cushion are connected by elastic straps e, one or more.

This pad or cushion is slipped over the case A, and it is made of such a length that the straps e will be stretched where it is fitted on the case, and the straps have sufficient tension to retain the pad or cushion in position.

By this simple means, furniture will be protected from abrasion, the pad or cushion serving as an efficient guard. It may be constructed at a small cost, quite inappreciable, and will, without doubt, be used by all who employ carpet-sweeping devices in their dwellings.

I do not claim broadly the use of rubber placed around the edges of brushes, &c., to prevent injuring furniture, for this is old; but, having thus described my invention,

I claim as new, and desire to secure by Letters Patent—

The placing around the body, A, of a carpet-sweeping machine, the pad C, connected at its ends by the elastic strip e, so as to be removable at pleasure, as herein described.

GILBERT F. TAYLOR.
